CONSTRUCTION MATERIAL AND METHOD
OF MAKING SAMEGilbert A. Hoggatt, Buffalo, N. Y., assignor to
Certain-Teed Products Corporation, New York,
N. Y., a corporation of MarylandApplication January 3, 1933, Serial No. 649,777
Renewed June 8, 1937

8 Claims. (Cl. 144—309)

This invention relates to construction materials, especially construction materials of fibrous composition. The invention has particular reference to wall boards with edges preformed to particular shapes in order to provide tight joints between adjacent boards.

The problems arising in the use of construction materials which must be laid as units or elements of greater or less size include the proper formation of the joints between such elements to insure continuity of a surface to be exposed or to prevent leakage or infiltration of air thru the structure, as well as to provide a proper support at the joint for superimposed surfacing materials.

Especially in wall boards which are used in abutted relation to form a continuous surface of the wall is it desirable or necessary that the continuity of the finished surface shall not be marred by the joint and also that the joint shall be strong and of such form as to prevent the leakage of air therethru, particularly when laid upon an outside wall. Moreover, the joint should be of such form in many cases as properly to support a plaster applied upon the wall board and over the joint. It is frequently necessary in such cases to provide a lock for the plaster which will assist in preventing cracking and breaking away of the plaster at the joint.

To accomplish such purposes in various types of construction materials and in wall board, it has heretofore been proposed to form the edges of the units or elements or of the wall boards with a so-called "shiplap" or rabbeted edge. Such units or boards may be laid with the rabbet of one unit lapping upon the reverse rabbet of an adjacent unit. Moreover, it has heretofore been proposed so to form such shiplap or rabbeted edges that when the units or the boards are so lapped a space of greater or less width is left between the adjacent edges of the units or boards on that side thereof which is to be exposed. This arrangement provides a recess into which plaster or other covering material may enter to form a lock for said covering material and makes possible a greater thickness of the plaster over the joint and thereby a stronger plaster joint.

The problem of expansion in such a construction, however, has not been suitably solved. While such a space as will provide for a lock in some cases will also take care of the expansion, nevertheless in many cases the abutment of the edge of one of the boards against the rabbet of the other board prevents the free expansion of the board which is necessary to prevent buckling and cracking or breakage of the plaster or covering material if such material is applied to the base surface. Moreover, the methods of producing the shiplap or rabbeted edge in many cases have been wasteful, particularly when making

provision for the space to form a lock for the plaster or covering material.

One object of the present invention, therefore, is to provide a form of shiplap or rabbeted edge for covering units or for wall boards which will incorporate the features of the forms of units and wall boards heretofore proposed but which will properly take care of the expansion.

Another object of the invention is to provide a method of making such rabbeted edge units or wall boards which will avoid waste of material and secure a production thereof at low cost.

In order to provide more effectively for the expansion which occurs in construction units and which results in buckling of the units or cracking of the surface thereof or cracking and breaking away of materials such as wall plasters applied thereto, the present invention proposes a form of rabbeted joint in which provision is made for expansion of the joint by means of a space between portions of the adjacent edges of adjacent units while other portions of the edges are in substantial abutment. The edges, however, are so formed that the portions in abutment may yield under the force of expansion without undue deformation or distortion of these portions to affect adversely the covering material applied thereto. Provision is made, therefore, both for the lock of the covering material such as plaster and for the expansion of the base unit such as a wall board. Cracking and breaking of the plaster or covering material at the joint are thereby prevented and buckling of the units, and consequent cracking of the face of the covering material or plaster which occurs when the base is not free to expand is also prevented.

The method of the invention comprises the severing of the material from which the unit is to be formed in such a way as to remove a minimum of material, as by a fine saw cut, and the subsequent separation of the two portions of the material along a line connecting the cuts.

In the formation of a rabbeted edge two such saw cuts may be made transversely of the surface of the unit on opposite surfaces of said unit, said cuts being spaced from each other in a direction parallel to the surfaces. The cuts do not extent thru the unit from one surface to the other and the line of severage or cleavage substantially connects the inner ends of the two cuts in the body of the material.

The invention will be more clearly understood from the following description taken in connection with the drawing of which:

Figure 1 shows in one embodiment of the invention an assembly of units having rabbeted edges;

Figure 2 shows the usual method of producing rabbeted edges;

55

60

Figure 3 shows the assembly of such units produced in the usual manner;

Figures 4 and 5 show the method of producing the rabbeted edges according to the invention;

Figure 6 shows a modified form of the units of the invention; and

Figure 7 shows an assembly of the units formed as in Figure 6.

In Figure 1 is shown in cross section one embodiment of the joint of my invention illustrating the application of the invention to a joint between wall boards. The wall board 1 is formed at its left hand edge in Figure 1 with a rabbeted recess provided by the surfaces 2 and 3. The tongue 4, of which the surface 2 forms the surface to be lapped upon the rabbeted edge of an adjacent board, is formed with a bevel surface 5 extending from the V-shaped edge 6 reversely upon the tongue 4. The thickness of the tongue 4 is approximately one-half the thickness of the board 1, and correspondingly the depth of the surface 3 is approximately one-half the thickness of said board.

At the opposite edge of the board 1 and in the reverse hand from the tongue 4 is formed the tongue 10 having an end surface 11 and a longitudinal surface 12. The height of the surface 11 is approximately one-half the thickness of the board. Thus the surface 12 is about at the middle of the thickness of the board. From the inner end of the surface 12 of the tongue 10 a bevel surface 13 extends inwardly toward the center of the length of the board but outwardly toward the upper surface 7 thereof to form with the surface 12 an obtuse angle. The angle of the bevel surface 13 with respect to the upper surface 7 of the board may be substantially the same as that of the surface 5 with said upper surface 7. However, if desired, the angles of these two surfaces may be different to suit particular conditions.

It will be noted from Figure 1 showing three such wall boards, one lapped upon the other, that the V-shaped edge 6 substantially abuts against the bevel surface 13 of the adjacent board. As the surfaces 2 and 12 are substantially longitudinally of the width of the board, these surfaces in adjacent units may move with respect to each other as in any shiplap construction. While these surfaces 2 and 12 have been shown as straight lines, they may be otherwise formed to suit different conditions provided the form of one with respect to the other is such that the overlapping tongue 4 of one board may move upon the overlapped tongue 10 of the adjacent board without substantial distortion of the tongues or substantial movement transversely of the surfaces of the boards. As the V-edge of the overlapping tongue 4 moves against the bevel surface 13 of an adjacent board under the force of expansion, a slight yielding or compression or even a slight crushing of such V edge may occur. As the edge 6 presents only a small amount of material against the surface 13, such yielding or even such crushing will not produce substantial deformation of the joint and plaster or other covering material applied upon the surface 7 and extending into the recess 15 between the surfaces 5 and 13 of adjacent boards will not be subject to an extreme force which will tend to crack the plaster at the joint and to cause it to chip off or break away.

While heretofore it has been proposed to use boards presenting a recess, such as that shown at 75 15 in Figure 1, in such prior constructions the

edges of the boards have been so formed that when the V edge 6 abuts the surface 13 the edge 11 will abut the surface 3 of the rabbet of the adjacent board. It has been found to be difficult to persuade workmen to leave space for expansion as it is easier to abut the boards when laying. Thus no provision has been made for expansion of the board because the abutment of the surfaces 11 and 3 prevent relative movement of said boards. In the present invention, as shown in Figure 1, a space is left between the end edge surface 11 of the tongue 10 of one board and the surface 3 of the rabbet of the overlapped board. When expansion of the boards takes place the edge 11 may move toward the surface 3 without bringing pressure thereon which will cause the boards to buckle or which will bring upon the joint forces which will tend to destroy the joint and cause cracking of the plaster applied thereto. It now should be clear that to provide the space between the surface 11 and the surface 3 it is necessary to form the surface 12 of the overlapped tongue 10 on one edge of the board with less length in the direction of the width of the board than the length in said direction of the surface 2. As may be seen in Figure 1, the difference in length of the surface 2 and of the surface 12 in the overlapped arrangement of the boards leaves the necessary space between the surface 11 and the surface 3 for expansion of the boards when the V edge 6 is abutted against the bevel 13.

As a particular example of the proportions which are practicable for the embodiment of the invention, those suitable for a wall board may be given. For so-called insulating lath which is used as a base for plaster or stucco, sheets or panels of the standard size of 96 inches length by 48 inches width may be reduced to smaller panels of approximately 48 inches by 16 inches to form the insulating lath. The width of shiplap boards, shown in the figure by the dimension A, in this particular example correspondingly would be approximately 16 inches from the V edge 6 to the corner formed by surfaces 12 and 13. In the ordinary laths the amount of material removed by the saw cuts necessary to cut the panel into the smaller laths would have to be allowed for. As an example of the dimensions necessary for the rabbeted edges, the following may be given: For a thickness of board about $\frac{1}{2}$ " the length of the surface 2 may be about $\frac{1}{2}$ " and the length of the surface 12 may be about $\frac{1}{4}$ ", thus leaving a space of approximately $\frac{1}{4}$ " for expansion. In a board of such a thickness the depth of the surface 3 is approximately $\frac{1}{4}$ " and similarly the dimension of the surface 11 is approximately $\frac{1}{4}$ ". Thus the surfaces 2 and 12 are positioned substantially at the center of the thickness of the board. The angle of the bevel surfaces 5 and 13 may be conveniently 45 degrees or in some cases the angle which these surfaces make with the surface 7 upon which plaster is to be applied may be approximately 120 degrees. Various modifications of the dimensions may be made within the scope of the invention, and in order to insure alignment of the surfaces 7 slight clearances between the surfaces 2 and 12 may be provided for. Moreover, in different forms of units different dimensions and clearances and different angles of the bevel surfaces may be used. It will be apparent that a movement of one board with respect to the other may produce a compression or a crushing of the V edge 6 upon the surface 13 of the ad-

acent board but that ample space is allowed between the surfaces 11 and 3 for such expansion without bringing the surfaces 11 and 3 into contact.

5 Figures 2 and 3 illustrate the present method of forming shiplap edges and the method of dividing a material, such as a wall board, into smaller portions having such edges. In some cases the cut 16 may be made in the face 17 of the board and a similar cut 18 may be made in the opposite face 19. If these cuts are suitably positioned with respect to each other and if the depth and width of the cut are sufficient, the two portions of the board may be cut apart in forming the cuts 16 and 18. In some cases it may be necessary to make an additional cut through the board in order to separate the two portions thereof if the cuts 16 and 18 do not meet and cut through the material. Usually, however, in the present practice the sections are first cut from the panel and the rabbets then are formed on each piece. In any case, it will be clear that the amount of material which is wasted is that represented by the full width of the cut 16 or of the cut 18 and that as well care must be taken to cut through the board or additional operations become necessary. When the separated pieces are lapped upon each other as in Figure 3, it will be clear that the amount of area covered by the boards is as much less than the area of the original material as the sum of the cuts at one face of the board.

30 In Figure 4 is illustrated the method according to the invention of dividing material into smaller portions so as to avoid the waste of the material usually necessary to form the rabbeted edge. A simple, quick and convenient method of forming such rabbeted edges is provided. The method is illustrated in this figure in connection with wall board having a body structure such as will permit cleavage longitudinally, that is, in a line extending in the same direction as the face of the boards. Such a body structure is provided in many types of construction materials including wall boards which have a laminated structure or those which are constructed in a felting or matting operation to produce a more or less homogeneous or "monolithic" body structure, which structure has a grain or an arrangement of the fibres longitudinally of the board. Such body structures, whether in fibrous materials or in other materials, make possible the cleavage of the body structure longitudinally of the board. The invention comprises wall boards and other construction units and materials which have a body structure which makes possible the separation of the material of the unit or board along such so-called longitudinal lines. For example, in a wall board of laminated construction, whether of fibrous or other material, the method of the invention finds application to produce the forms of rabbeted edge which heretofore have been used in the art or those proposed by the present invention as described above.

65 In Figure 4 illustrating the method of forming such rabbeted or shiplap edges in a wall board a narrow saw cut 20 is made part way thru the board from one face 21 thereof. This cut is shown as being made at right angles to the face 21 of the board, but the cut may be made at any suitable angle, depending upon the result desired. At 22 is shown a second saw cut made part way thru the board from the opposite face 23 thereof. It will be noted that these cuts are not in line and do not meet at the center of

the board. However, they do extend to a line of cleavage shown by dotted line 25 extending longitudinally of the board, that is, in the general direction of the faces 21 and 23. In its simplest form the invention comprises the formation of cuts, as has just been described, and the subsequent cleavage along the line of cleavage 25 so as to separate two portions of the board 1 from each other. In the formation of a simple shiplap or rabbeted edge, such as is used in wall boards, this cleavage may readily be accomplished by a flexure of the panel from which the two pieces of board are to be formed so that the force is applied to the line of cleavage and the separation takes place along this line. In Figure 5 is a simple illustration of the step of flexure 15 to secure separation of the two portions of the board. The small pieces at the edge of the panel from which the boards or laths are made similarly may be removed by cleavage.

20 It will be apparent that the saw cuts 20 and 22 may be made simultaneously with suitable apparatus by running the panel or sheet of wall board or other construction material both under one saw, to produce the upper cut 20, and over a saw placed beneath the cutting table, to produce the lower cut 22. Moreover, in cutting a panel into a number of units a plurality of such sets of saws may be used so that in a single pass of the material thru the apparatus all the necessary saw cuts are made. Subsequently by a simple action of bending or flexure of the portions on each side of the pair of cuts the cleavage or breakage of the board along the cleavage line 25 separates the several sections or portions. Such a flexure or bending of the material may be accomplished by hand or by suitable guide devices placed subsequent to the cutting saws in the movement of the panel or sheet thru the apparatus. The method of my invention, however, is not limited to the particular devices used for forming the cuts or of separating the portions on either side thereof, but embraces the methods practiced by all such devices or operations.

35 40 45 In order to form the V-shaped recesses or beveled surfaces which have been described above in connection with Figure 1, a cutter or in some cases a grinding wheel which has a form in section to provide at its rim a V of the desired angle and of the desired position with respect to the plane of rotation, i. e., whether symmetrical with said plane of rotation of said cutter or otherwise, may be used. Thus also in one operation a bevel edge board may be produced in the manner described in connection with Figure 4. Moreover as 50 may be seen from Figures 1, 6 and 7 by using a saw or cutter of proper width for the lower cut 22 the width of the space between the surfaces 11 and 3 as shown in Figure 1 may be made such as to leave room for expansion of the boards. By suitably positioning the saws or the cutters or the grinding wheels, the dimensions desired for the surfaces 2 and 12 as well as for the relation of the other surfaces of the edges of the board may be obtained. All such adjustments 55 60 65 70 75 may be practiced with variations of both the kinds of devices used and the particular action thereof within the scope of my invention.

In applying the invention in the production of units or elements of some kinds of material the cleavage or breakage of the body structure of the material along the line of cleavage may result in surfaces which are not sufficiently smooth. These surfaces may result from the tearing away of fibres from one side by the other 75

or from the interspersed relation of the particles forming the body structure, said particles having parts thereof extending over the line of cleavage into the body structure on the opposite side thereof. In some cases such rough surfaces are not a disadvantage, particularly when the units or elements are to be lapped again in the same position as that in which they were broken apart, as shown in Figures 1, 4 and 5. In some cases, however, it is desirable to form one of the saw cuts with a wide width and the other with as little width as is practicable. The difference between the widths of the saw cuts will provide for a recess between adjacent boards at one surface thereof when the other portions of the rabbets are abutted, as shown in Figure 7. In such a case it may be necessary when a rough surface results from the breakage or cleavage to smooth these surfaces by running the separated units or portions over an emery wheel or other device to bring the rough surface down substantially to the center of the width of the board.

This is the more necessary when units such as wall boards are to be arranged upon a supporting structure without any superimposed coating such as plaster which will cover the joint although in some cases it may be necessary to smooth the rough surface in order to insure that the exterior surfaces of two adjacent boards shall be aligned. Such may be the case when a paneling strip, such as a wood strip, is placed over the joint. Wall boards or insulating laths having rabbeted or shiplap edges may be produced for such use by the simple operation of cutting the slots and breaking the sections apart as has been described above.

While the invention has been described and illustrated more particularly in connection with wall boards, it is applicable to other types of construction units and construction materials. In all such materials, whether of granular or fibrous or other body structure, which have or may be formed so as to have a line of cleavage extending generally in the same direction as the faces to be exposed, the method of the invention may be utilized by forming recesses, whether by cuts into the body of the material or recesses molded or otherwise made in the face of the material before separation. Such recesses or cuts reach into a cleavage line along which the adjacent portions may be separated to form the rabbet on the edge of each piece. In particular, however, the invention is useful to the formation of shiplap edges or panels of wall boards of fibrous materials which have not a great resistance to cleavage along the layers or along the grain of the fibre extending generally in the direction of the faces of said panels or boards.

What is claimed is:

1. The method of forming rabbeted edges in a structural unit which comprises cutting part way thru the material from which the unit is being made to a line of cleavage therein, cutting thru said material from another side thereof to meet said line of cleavage at a point thereon different from that at which the first cut meets said cleavage line, and so applying force to said material as to cause cleavage thereof along said cleavage line joining said cuts.
2. The method of forming rabbeted edges in a structural unit which comprises cutting part way thru the material from which the unit is being made to a line of cleavage therein, cutting thru said material from another side thereof to meet

said line of cleavage at a point thereon different from that at which the first cut meets said cleavage line, and so applying force to said material as to cause flexure thereof to produce cleavage along said line joining the cuts.

3. The method of forming rabbeted edges upon structural panels having a body structure providing cleavage lines longitudinally of the plane of the panel, which comprises cutting the panel at points separated longitudinally thereof from opposite faces thereof and transversely to said faces at least to a depth such that each cut meets substantially the same line of cleavage, and separating said portions on either side of the cuts by cleavage along said cleavage line.

4. The method of forming shiplap edges upon fibre wall board having the grain of the fibre for the most part extending in the same general direction as the face of the board, which comprises forming a cut part way thru the board transversely to one face thereof, forming a second cut part way thru the board transversely to the opposite face thereof, said cuts being laterally spaced and extending substantially to a grain of the fibre connecting said cuts, and separating the portion of the board at one side of the cuts from that at the other side of the cuts along the grain of the fibre lying between said cuts.

5. The method of forming upon a structural unit rabbeted edges of unequal length of the rabbet, which comprises forming a relatively narrow cut of a length to extend only part way thru the material from which the unit is being made from one side thereof, forming a relatively wider cut laterally removed from said first cut and extending part way thru said material from another side thereof, and causing the material to separate substantially upon a line joining said cuts.

6. The method of forming upon a structural unit rabbeted edges of unequal length of the rabbet which comprises forming a cut extending part way thru the material from which the unit is being made from one side thereof, and forming a second cut laterally removed with respect to the line of said first cut and extending part way thru said material from another side thereof, and causing the material to separate substantially upon a line joining said cuts, the width of said second cut and the position thereof with respect to the line of said first cut determining the relation of the length of the rabbets.

7. The method of forming upon a structural unit rabbeted edges of unequal length of the rabbet, which comprises forming a relatively narrow cut of a length to extend part way thru the material from which the unit is being made from one side thereof, forming a relatively wider cut to extend part way thru said material from the opposite side thereof, said cuts being laterally offset from each other and being of such depth that if in alignment the bottoms of said cuts would substantially meet, and severing said material along a line joining the bottoms of said cuts.

8. A pair of structural members each having upon a face thereof a rabbet formed at an edge of the member, said members being formed of the same piece of material and having planes of cleavage generally like-extending with said faces, the lapping surfaces of said rabbets of said members being the complementary cleavage surfaces along a common plane of cleavage of said material.

GILBERT A. HOGGATT.
